UNITED STATES PATENT OFFICE.

FRITZ GUTZMANN, OF CHARLOTTENBURG, GERMANY, ASSIGNOR TO C. LORENZ AKTIENGESELLSCHAFT, OF BERLIN-TEMPELHOF, GERMANY.

HIGH-FREQUENCY APPARATUS.

Application filed August 26, 1926, Serial No. 131,576, and in Germany September 19, 1925.

The present invention has reference to improvements in high frequency apparatus, and it relates more particularly to means for cooling iron-cored apparatus of this character, especially frequency transformers.

It is of recognized importance to properly cool electrical apparatus containing magnetically stressed iron, for the purpose of absorbing or dissipating the heat generated by the losses in the iron and in the winding. For this purpose, as is well known, transformers are bodily immersed in a flowing or stagnant cooling medium, such as oil.

My invention is directed to a method and means for cooling apparatus containing magnetically highly stressed iron, such as for instance frequency changers used for stepping up a fundamental (natural) frequency to higher frequencies, keying or telephony chokes, and like apparatus for controlling high frequency currents, in which the excessive iron heat, due to the high frequencies, must be actively removed to insure efficient operation of the device.

According to my invention I forcibly cause a cooling medium, liquid or gaseous, to circulate between the iron core to be cooled and its winding, so that the iron mass is completely surrounded by the cooling medium, whereas in the conventional oil baths, the oil reaches the iron surface only in spots through the interstices in the surrounding winding, leaving the principal heat absorption to outwardly directed convection through the copper winding.

My invention will readily be understood from a description of the accompanying drawing, in which the improvement is shown, by way of example, as applied to a frequency transformer, Fig. 1 being a longitudinal section and Fig. 2 a cross-section through the arrangement. In Fig. 1 the winding is omitted.

In the two figures the reference numeral 1 denotes the annular iron core formed of thin wires wound upon the cylinder 2, with the windings 3 and 11 arranged to form the primary and secondary of a toroidal coil, in well known manner. The iron core 1 is suitably floatingly suspended within an annular cooling chamber 4, formed by the inner wall 7 and the outer wall 8, and side walls 9 and 10 respectively, and provided with influx and efflux ports 5 and 6 respectively. The cooling chamber is preferably made of in-

sulating material so that the windings 3 and 11 can be applied to it directly. The cooling oil is forced in through port 5, passes through the annular cooling chamber 4 in the direction of the arrows, and issues at 6, and is then preferably cooled and used over again in continuous circulation. The cooling medium, interposed between the iron core 1 and the windings 3 and 11 prevents to a high degree heat transference from iron to winding, and the winding space can thus fully be made use of without having to consider the admission possibility of the cooling medium to the core through the winding.

A further advantage is that now the loading factor of the iron can be enhanced, that is to say the ratio between the iron cross-section and the winding cross-section, since now the oil sufficiently insulates the iron relative to the winding, which means also less danger of high stray voltage.

In addition to cooling the iron core by the positively moved cooling medium for cooling the iron mass, I immerse the transformer in the conventional oil bath for cooling the winding. The movement of the cooling medium through the cooling chamber surrounding the iron core may be caused by any suitable means, for instance by an electrically driven circulatory pump, which drive with its connections to the cooling chamber form no part of this invention and thus need no special illustration or description here.

The requirements for high frequency transformers differ from those for transformers adapted for ordinary frequencies, as follows:—

The windings must be placed very close to the iron core, to reduce stray fields.

The windings must be well insulated from the iron core due to the high voltages involved;

(It so happens that good electric insulators are usually also good heat insulators, but this can be turned to advantage because heat insulation is advisable since the iron core is usually at a high temperature);

And the usual materials such as cotton, silk and rubber must be excluded from the transformer because they can only carry about 100° C., just a fraction of the 300° C. at which high frequency cores normally operate.

Moreover, in order to reduce the stray

field the iron core is also made of very small dimensions so as to reduce the overall volume of the transformer winding to facilitate closeness of spacing.

All of the above difficult requirements are met by the use of oil for the electric and heat insulator and at the same time by the circulation of the oil to remove the heat resultant from iron losses due to eddy currents as described in detail above.

10 What I claim is:—

1. In high frequency apparatus, an iron core, a cooling chamber spacedly surrounding said core, influx and efflux ports in said chamber, and a winding surrounding said chamber.

15 2. In high frequency apparatus, a cooling

chamber of insulating material adapted for the passage therethrough of a cooling medium, influx and efflux ports in said chamber, an iron core floatingly supported within said chamber, and a winding surrounding said chamber.

20 3. A high frequency apparatus comprising windings and an iron core and having a support to space the windings and core apart 25 to permit a cooling fluid to be circulated between the iron core and windings in all-over contact with the core surface and having means to keep the cooling fluid out of contact with the winding.

25 In testimony whereof I affix my signature.

FRITZ GUTZMANN.
